ABSTRACT: A method for inserting chips into the edge of record cards or the like. A pouch is skived into the edge of a card into which a chip is inserted. The pouch is then sealed by applying pressure and heat. The assembly is then abraded to the original thickness of the card.

FIG. 7

FIG. 8A**FIG. 8B****FIG. 8C****FIG. 8 D****FIG. 8 E**## METHOD OF CHIP INSERTION

BACKGROUND OF THE INVENTION

The present invention relates to record cards for information retrieval and more particularly to record cards which are selectable by means of indicia attached to said cards.

The prior art shows generally two methods of attaching indicia in the form of chips to record cards. One method is to attach a chip to the surface of a card by adhesive means. However, a major disadvantage of the prior art method is that in handling by machine operators and during machine processing of the cards, the chips are often separated from the surface of the card causing the indicia to be lost.

Another known method is a lamination process in which two sheets approximately one-half the normal thickness of the record card or approximately 0.003 inch, are coated with adhesive material on one side of each of said half thickness sheets, a chip is placed between said coated sides and the entire laminated assembly is then heated and pressed to achieve a complete card with indicia attached. This method has the major disadvantage of having the lamination separate during handling or machine processing so that the entire card is destroyed. Further, because of irregularities in the adhesive material, the thickness of the card is not uniform across its entire length and width.

It is, therefore, the principle object of the present invention to imbed chips in a unit record card in an improved manner.

A further object is to attach chips to a record card in an improved manner where the assembly thus formed will be able to withstand handling and machine processing with no separation of the chips from the card.

SUMMARY OF THE INVENTION

In accordance with the above objects, a record card is provided with an indicia bearing chip inserted into the edge of said card so that said card may be identified and selected by means of said chip. Further, a method is provided in which a pouch is skived into the edge of a sheet with a very sharp and thin cutting blade deep enough to accept a chip. The chip which is precoated on both sides with heat and pressure sensitive material is inserted into the skived card. Heat and pressure are then applied to seal the chip to the sheet and to close the opening. The assembly is then abraded to approximately the original thickness of the card.

For the purpose of the present invention the term "skiving" means the separation of the fibers along the edge of a sheet to form a pouch therein.

The method of the present invention eliminates the problems of the prior art in handling of the cards by operators and in machine processing. The chip which has been inserted into the edge of the card is not exposed to forces which might tend to tear away a chip, which is merely attached to the surface of the card, nor is the card, being a single sheet, as likely to be damaged as the laminated card in machine processing.

One major advantage of the present invention is that precision in the order of ± 0.002 inch can be achieved in the position of the chip as opposed to ± 0.250 inch in the prior art.

A feature of the present invention is that there are many uses for cards made by this method. Among these are: (1) cards in which the chip is a reinforced piece of magnetic tape containing data which can be erased and new data written; (2) cards wherein the chip provides a means for selecting a card from a deck by magnetic means; (3) cards wherein, in addition to providing selection, the chip also contains data storage capability.

While the invention has been particularly shown and described with reference to a preferred embodiment thereof, it will be understood by those skilled in the art that various changes in form and details may be made therein without departing from the spirit and scope of the invention.

DESCRIPTION

The foregoing and other objects, features and advantages of the invention will be apparent from the following more particular description of preferred embodiments of the invention, as illustrated in the accompanying drawings.

In the Drawings

FIG. 1 is a sectioned top view of an apparatus to perform the method of the invention.

10 FIG. 2 is a sectional view of the hopper and card feed.

FIG. 3 is a sectioned view of station 2 which is the skiving station.

FIG. 4 is a sectioned view of station 3 which shows the details of chip insertion.

15 FIG. 5 is a sectioned view of station 4 which shows the details of the heat sealing.

FIG. 6A is a sectioned view of station 5 which shows the abrading of the card with the chip inserted.

20 FIG. 6B is a side view of the card with chip inserted with the abrading roller applied.

FIG. 7 is a sectioned view of station 6 showing the card and hopper ejection.

25 FIG. 8 shows the method schematically in 5 separate drawings.

FIG. 8A shows schematically the start of the skiving operation at station 2.

FIG. 8B shows the end of the skiving operation at station 2.

FIG. 8C shows the chip inserted at station 3.

30 FIG. 8D shows the heat sealing at station 4.

FIG. 8E shows schematically the abrading at station 5.

Referring to FIG. 1, a chip imbedding machine 10 is shown which includes a main frame 12, and a turntable 14, rotatably mounted thereon. The main frame has fixedly mounted thereon six equally spaced stations. These stations include a card feeding station 20, skiving station 30, a chip insertion station 40, a heat-sealing station 50, an abrading station 60, and a card eject station 70, each of which will be hereinafter explained in greater detail. These pockets are capable of retaining a record card in a precise position. Turntable 14 can sequentially step the card around to each of the equally spaced stations so that work can be performed on the card. Turntable 14 is stepwise rotated by a stepping motor which is not shown. Said stepping motor operates when all microswitches 23 have been activated by the tools at all six stations moving to their initial or nonwork positions. In this condition a complete circuit is made to apply the necessary voltage to the stepping motor to allow it to index turntable 14 through an angle of 60° .

50 FIG. 2 shows in detail the card feeding station 20. Hopper 21 which is mounted on main frame 12 holds a stack 28 of cards. The bottom most card 18 of the stack is fed from the hopper to card pocket 16 by feed finger 22, which is movable mounted beneath the stack of cards on main frame 12. Microswitch 23 is mounted on main frame 12 in line with feed finger 22 in such a manner that when the feed finger returns to the initial or feed position, microswitch 23 is activated which causes the turntable to be advanced to the next station. Card 18 is fed into pocket 16. Pocket 16 holds the card in a precise position with respect to the various work stations fixedly attached to the main frame as the turntable is indexed. The card is held in position in the card pocket by means of a vacuum supplied to pocket 16 through lines 26 from main vacuum stem 25. Main vacuum stem 25 is mounted in the hub of the turntable 14 with supply lines 27 running to each of six pockets 16. A plurality of vacuum lines 26 provide the vacuum necessary to hold card 18 in the precise position and flat in pocket 16.

70 FIG. 3 shows in detail the card-skiving station 30. The skiving blade 31 with the top retaining shoulder 32 is mounted in accurate dovetail slides 34. Said slides being mounted by housing 36 to main frame 12 in such position that blade 31, when advanced, skives a pouch 37 into each of longitudinal edges 19 of card 18. Skiving knife 31 is moved by air pressure

in air cylinder 39 which is mounted in housing 36. Microswitches 23 are mounted on frame 12 in line with skiving knife 31 so that when the skiving knife returns to its initial position, the switch is activated which in turn causes the turntable 14 to move through a 60° angle to the next station.

FIG. 4 shows a side view of the chip insertion station. Card 18 with pouches 19 caused by the skiving, is then positioned for chip 41 to be inserted into pouch 19. Chip feed knife 42 is mounted in accurate dovetail slides 43 so that when activated said knife urges a coated chip 41 into the pouch 37 on card 18. The chips 41 are contained in a stack 44 in chip hopper 46. Microswitches 23 are activated in the same manner as at the previous station so that when the chip feed knife retracts to its initial position, the microswitch is operated to move the turntable 14 to the next station.

FIG. 5 shows a side sectional view of the heat sealing station 50. When turntable 14 comes to rest with a card 18 in position for the heat sealing operation to be performed, heat is applied to heat pad surfaces 51 which are mounted on the bottom of heat block 52 by calrod heater 53, which is imbedded within heat block 52. Heat block 52 is mounted on slide 55 above the card. Slide 55 is movable in the vertical direction and controlled by air cylinder 57 mounted above slide 55 on housing 56. Cable 54 supplies power to heater 53.

FIG. 6A shows the abrading station 60. Abrading wheels 61 are attached to abrader motor 62 mounted in support housing 63.

Venier 64 mounted on top of support housing 63 controls the height of the abrading wheel 61. Support housing 63 is fixedly mounted on main frame 12. The rotary motion of turntable 14 past the abrading station 60 is used to insure the entire card is abraded by the rotating abrading wheels 61.

Referring to FIG. 6B, the motion of the abrading wheel 61 is shown passing over the chip 41 imbedded in card 18. Note that the direction of rotation of abrading wheel 61 is opposite to the direction of card travel at the point of contact. The abrading operation removes the excess build up above 0.007 inch due to the increased thickness of the chip and the card. The abrading operation is performed as turntable 14 is moving from the heat-sealing station 50 to the card eject station 70 and not while the turntable is in a stopped position.

Referring to FIG. 7, the card eject station 70 will now be described. Card ejector finger 71 movable mounted in ejector housing 72, is controlled by air pressure from air cylinder 76 which is mounted in ejector housing 72. When turntable 14 has stopped at eject station 70, microswitch 75 is activated thereby breaking the vacuum and allowing card 18 to be released. Eject finger 71 urges card 18 into stack 73 contained in hopper 74 by contacting longitudinal edge 19 of said card and moving said card in a horizontal direction to the card hopper.

The positioning method of the card and skiving is illustrated in FIGS. 8A through 8E. Referring to FIG. 8A, the skiving blade 31 is shown in position to form a pouch in longitudinal edge 19 of card 18.

FIG. 8B illustrates the skiving operation with the skiving tool blade inserted in the card. It is this step which forms pouch 37 in the longitudinal edge 19 of card 18.

Referring to FIG. 8C, the chip 41 is then inserted in pouch 37. The assembled chip and card is then sealed in position by heat-sealing operation. This heat sealing step closes the opening of the pouch leaving the chip in precise position in the pouch.

Abrasing wheels 61 are shown in FIG. 8E for carrying out the step of smoothing the high spots caused by the insertion of the chip 41 into the edge of the card.

The method of inserting a chip into the edge of a sheet comprises the following steps:

First, a pouch is skived into the edge of a sheet whose thickness is approximately 0.007 inch, by a very sharp and thin blade;

second, a chip is precoated on both sides with an adhesive coating and said chip is inserted into said pouch;

third, heat and pressure are applied to said sheet to seal said chip to said sheet and to close the pouch, typical parameters of the heat-sealing operation are, temperature 350° F.; applied pressure 35 pounds per square inch, and application time equal to one second;

fourth, the assembled chip and sheet are abraded to remove built-up material in excess of the original thickness of the sheet.

10

OPERATION

Referring now to FIG. 2, the operation of a preferred embodiment for performing the method of the invention will be described. In the preferred embodiment there are six-card pockets 16 equally spaced around a movable turntable 14. The various operations to be described may all be occurring simultaneously on different cards at various stations. For the purpose of this description, the card referred to may be considered the first card operated on at each station.

20 A record card 18 is fed by card feed finger 22 from the bottom of a stack 28 of record cards 18. Card feed finger 22 moves in a direction perpendicular to the longitudinal edge 19 of card 18 to urge said card into card pocket 16. Card pocket 16 is constructed to very close tolerances to hold the record card in a precise position with respect to each of the operational stations. When the card is situated in card pocket 16, card feed finger 22 is moved back and activates microswitch 23 thereby causing a vacuum to be applied which holds the card flat and securely in position in card pocket 16. The vacuum remains applied throughout the successive operations until the assembly is complete and the card is to be ejected at the card eject station 70. When the operation of the card feed station is completed, the stepping motor is activated thereby causing turntable 14 to rotate through 60° so that the card under consideration appears at the card skiving station 30.

Referring now to FIG. 3, the operation of the card-skiving station will be described. Air pressure applied to cylinder 38 forces skiving knife 31 into the longitudinal edge 19 of record card 18. Top retaining shoulder 32 mounted above the skiving blade 31 provides a surface against which the separate fibers of the card can move without separating or tearing. A pouch 37 is thus formed in the longitudinal edge 19 of the card 18. When the pouch has been skived, the skiving tool is then moved back to its initial position causing microswitch 23 to be activated thereby causing turntable 14 to be rotated and the card under consideration moved to chip insertion station 40.

Referring now to FIG. 4, at chip insertion station 40, the bottommost chip 41 of a stack 44 of chips is urged into the pouches 37 on each longitudinal edge of the record card. Chip feed knife 42 which is mounted in accurate dovetail slides 43 is then moved back to its initial position contacting microswitch 23 which then allows the turntable to rotate to the heat sealing station.

55 Referring now to FIG. 5, the heat sealing operation is performed by heat pad surfaces 51 being forced downward against the areas on the card wherein the chips are contained.

Power is supplied to calrod heater 53 imbedded in heat block 52 by cable 54. Air cylinder 57 controls the movement of slides 55 against the card.

Typical parameters for the heat sealing operation are as follows: Temperature of heat pad surface 51 equal to 350° F.; applied pressure equal to 35 pounds per square inch; application time equal to one second. After application of heat and pressure at the heat-sealing station 50, two-way cylinder 57 moves the heat block away from the cards causing slide 55 to contact microswitch 23 which in turn activates the stepping motor and causes the turntable 14 to rotate.

70 Referring to FIG. 6A, abrasing wheels 61 which are driven by electric motor 62 mounted on support 63 rotate in a direction opposite to the rotation of turntable 14. The abrasing operation is performed while turntable 14 is moving past the abrasing wheels. A venier adjustment 64 is provided to 75 control the position of the abrasing wheels with respect to the

card and thereby control the thickness of the card in the area of the chip. The typical dimension for the thickness of the card is approximately 0.007 inch.

Referring now to FIG. 7, turntable 14 is rotated until the card under discussion is placed at the card eject station 70. When turntable 14 stops at card eject station 70, the card feed limit switch 23 is activated. Air under pressure is supplied to air cylinder 76 mounted in ejector housing 72. The cylinder causes ejector finger 71 to move forward until it trips the vacuum and limit switch 75. The vacuum and limit switch breaks the vacuum holding the card and reverses the direction of air to the other end of the air cylinder 76 which reverses the direction of ejector finger 71. The ejector finger then urges the card 18 into the stack 73 contained in card hopper 74. When ejector finger 71 completes this operation, limit switch 23 is activated which completes one cycle of operation of the apparatus.

It must be noted that other cards are being operated on at the various stations in sequence.

Although what has been described is a preferred embodiment of an apparatus to perform the method of the invention, the method is not restricted to this apparatus. Any apparatus where the necessary steps can be performed in the proper sequence is suitable to meet the objects of the invention.

In general, the method consists of skiving a pouch into an edge or a plurality of edges of a sheet, inserting a chip into said pouches, sealing said pouch with said chip imbedded therein,

and abrading said assembled sheet with chip imbedded therein to the original thickness of said sheet so that said sheet may be used for any purpose which requires an indicia securely imbedded within the sheet.

5 What is claimed is:

1. A method of imbedding a magnetic metallic chip into the edge of a record card comprising the steps of:
  - a. skiving a pouch into the edge of said record card;
  - b. applying an adhesive coating to both sides of said magnetic metallic chip;
  - c. inserting said magnetic metallic chip into the pouch formed by said skiving;
  - d. heating said record card with said magnetic metallic chip inserted therein to seal the chip to said card;
  - e. abrading said record card to achieve approximately the original dimension of said card.

10 2. A method of imbedding a chip capable of bearing information into edge of a carrier having a thickness of less than 15 milli-inches, comprising:

- 20 a. skiving a pouch into the edge of said carrier; applying an adhesive coating to both sides of said chip;
- b. inserting said coated chip into a pouch formed by said skiving;
- c. heating said carrier to melt said adhesive coating;
- d. applying pressure to said carrier to seal said chip within said carrier.
